CLAIM

I claim the ornamental design for a lantern, as shown and described.

DESCRIPTION

FIG. 1 is a perspective view of a lantern.

FIG. 2 is a front view of the lantern of FIG. 1.

FIG. 3 is a rear view of the lantern of FIG. 1.

FIG. 4 is a side view of the right side of the lantern of FIG. 1.

FIG. 5 is a side view of the left side of the lantern of FIG. 1.

FIG. 6 is a top view of the lantern of FIG. 1; and, FIG. 7 is a bottom view of the lantern of FIG. 1.

The broken lines show unclaimed portions of the article and form no part of the claimed design.

1 Claim, 5 Drawing Sheets(56)
